JOSEPH L. BUCKLEY, OF DAVENPORT, IOWA.

METHOD OF ORNAMENTING BRICK

1,195,649.

specification of Letters Patent. Patented Aug. 22, 1916.

Application filed November 8, 1915. Serial No. 60,260.

To all whom it may concern:

Be it known that I, JOSEPH L. BUCKLEY, a citizen of the United States of America, and resident of Davenport, Scott county, 5 Iowa, have invented a certain new and useful Improvement in Methods of Ornamenting Brick, of which the following is a specification.

My invention relates to a method for ornamenting bricks, in which process is involved the use of the ordinary stiff-mud brick machine of the type that produces a continuously formed column of clay that is cut into brick size, ready for burning, 15 and has for its object the provision of a method for embossing or projecting figures of ornamentation, in relief, on one or more faces of the clay column, whereby a finished brick is produced, having one or more of 20 its faces ornamented in simulation of the appearance of "oak bark."

To remove the undesirable slick, silvery surface formed on the clay column by the passage of the moistened mass through the 25 smooth die, and to produce the present day brick with the much desired roughened surface, it is the common practice to remove a slice of considerable thickness from the upper surface and edges of the column (as 30 these surfaces become the exposed faces of the finished brick when in a wall) leaving a raw and more or less ragged surface, or to tear the surface into ridges or furrows by passing same through a mass of sharp pointed pins arranged in front of the die of the 35 brick machine.

While the surface of the brick is roughened to the desired degree by the employment 40 of my method of producing "oak bark" brick, the surface is also highly ornamented by projecting portions of the surface, of considerable area, in sharply defined relief, with a raw, more or less ragged surface, as a background. While a design 45 of most any desired configuration could be embossed in relief on the surface of the brick by subjecting each individual brick to the pressure of a die press, the operation is not only expensive, but the product would 50 oftentimes prove unsatisfactory due to the lack of variety, as each brick would be an exact duplicate of the other. This lack of variety would prove exceptionally objectionable in a design simulating "oak bark."

55 In producing "oak-bark" brick, the slick, shiny surface of the clay column must be

completely separated from the column. This is best accomplished by scraping the exposed surfaces of the column as it passes from the die. The scraps or loosened portions 60 released by the scraping apparatus, when the scraping apparatus is properly positioned with respect to the edges of the die, take the form of elongated chips or shavings, with their edges more or less curled 65 up, and which arrange themselves with more or less regularity in rows transversely of the surface scraped. While a complete separation will thus be effected between the scrapings and the body of the clay column, 70 the moist sticky consistency of the clay mass, affords means whereby the shavings or scrapings retain their position on the column as assumed upon leaving the scraping apparatus. 75

To straighten out the more or less curled up edges of the shavings, and to more securely reunite them to the body of the column, whereby they will not become displaced when subjected to the action of the 80 cutting wires, in reducing the column to brick size, they are subjected to pressure immediately upon formation, and after leaving the brick-size cutting wires they are again subjected to pressure to cause them to 85 firmly adhere to the body of the finished brick and to square up any edges that may have become slightly torn up or roughened by the action of the cutting wires, thus projecting the shavings in sharp bas-relief 90 from the surface of the brick, with no two brick ornamented with exactly the same configuration.

The mechanism for ornamenting the face 95 of the brick by giving to it the semblance of "oak bark" may be used with brick machine of the ordinary stiff mud type. In Fig. 1 of the drawing is shown the perspective view of the device as applied to an ordinary stiff mud brick machine, parts of 100 which are diagrammatically shown. Fig. 2 is an enlarged view of the ornamental configuration in the process of formation.

The preferred form of the scraping and 105 pressing means are shown in the drawing as consisting of the brackets 7, which may be secured to any convenient point on the head 3, of the brick machine (a broken away section only of the head being shown) as at 8. These brackets may be of angular 110 form, and extending through the vertical members 9, are the threaded eye bolts 10.

Extending across the opening in the usual die plate 4, and in close proximity to the upper horizontal edge thereof, is the scraper 11, which may consist of a piano wire secured at its end to the eye bolts 10, through the medium of which it can be stretched taut by the aid of the nuts 12. To prevent bowing of the wire scraper at its center, to insure shavings or scrapings of uniform thickness, I provide the angle shaped bracket 13, which is secured at one end to the head 3, and has its other end in contact with the wire at about its center of length. The free end of this bracket may be made 15 to extend to a point on a plane with the lower side of the wire scraper, and may have its end drawn to a knife edge so that it will sever the transversely extending shavings into shorter lengths and thus more 20 closely simulate the appearance of "bark." The edges of the column are similarly scraped by the scraping wires 14, which may also be tightly secured in close proximity to the vertical edges of the die plate 4, 25 by eye-bolts passing through the horizontal member 15, of the bracket 7, at one end and to the bracket 16, at the other end.

When the clay column, which is expelled through the die plate 4, in the usual manner, 30 comes in contact with these scrapers, the surface is peeled off in shavings-like formations having irregular edges, more or less curled up, and the surface more or less crinkled longitudinally, and arranged in 35 a general transverse direction in substantially parallel rows as shown at *a a a*.

When the scrapers are positioned at too great a distance from the edge of the die in toward the opening, they function more 40 as cutters, severing an unbroken slice from the column, thereby negating the very end sought, that is, the formation of the shavings-like portions with their irregular outlines, crinkled surface, and curled up edges. 45 The discovery that the wires or cutters could be positioned at a point relative to the surface of the column where they would cease to slice off an unbroken mass, but 50 function as scrapers, bringing forth the disconnected, shaving-like formation, I consider the important feature of my invention. The exact point at which the slice separated, will disintegrate into the much desired disconnected shaving-like formation 55 is dependent in a large measure on the percentage of moisture in the clay and speed of travel of the column, it being the aim to produce as thick a shavings as possible. The brackets 7 and 16, may therefore be adjustably secured by providing same with the slotted holes 17, or by any other suitable means, whereby the scrapers may be properly positioned relative to the surface of the column.

Immediately upon converting the surface

of the column into the above described formation, means are provided to apply sufficient pressure thereto, whereby their more or less curled up edges are flattened out and they are more thoroughly reunited to the 70 body of the column, so that they may undergo the process of cutting to brick-size without appreciable displacement or injury. This pressure applying means may consist of the bracket 18 or the like, secured in 75 any suitable manner to the frame 19. Hinged to this bracket at about its center over the clay column is the roller 20, provided with the usual lamb's wool covering. The parts may be made of a weight that 80 gravity alone will produce the necessary pressure of the roller on the shavings, or the pressure may be produced by the use of an ordinary spring hinge.

After the column has passed through the 85 usual brick-size cutting device as shown at 6, the surface is again subjected to the weighted roller 21, suitably mounted to the rear of the cutting frame, whereby the shaving formations are firmly reunited to the 90 body of the brick and any unevenness or roughness that may have been caused by the cutting wires is smoothed out and obliterated, leaving the ornamentation clean cut and in sharp relief. The pressure applying 95 means to act upon the edges of the column may consist of the rollers 22, secured to the frame in any suitable manner as by the bracket 23.

If it be desired to ornament the face of 100 the finished brick but not the ends, the rollers 22 may be removed and the scrapers 14, adjusted farther in from the vertical ends of the die plate, so that it will cut off an unbroken slice of the column, permitting same 105 to drop to the floor, upon which it may be returned to the mixing machine. The smooth, shiny surface of the edges of the column (which become the ends of the finished brick) will thus be removed, leaving 110 a raw, more or less roughened surface.

Having thus described my invention, what I claim as new is:

1. The method herein described of making ornamental-faced brick, consisting in continuously forming a column of the plastic clay, continuously forming upon one face of the column a series of shaving-like fragments and irregularly spacing said fragments along said face, then reuniting the 115 fragments to said face by pressure, the pressure being sufficient to only attach the fragments to the column and not to obliterate them, thereby leaving the fragments in relief on the face of the column, and then severing 120 the column into the desired sizes.

2. The method herein described of making ornamental-faced brick, consisting in continuously forming a column of the plastic clay, continuously producing on one face of 130

- the column a series of irregularly-shaped and irregularly-spaced shaving-like fragments, then applying sufficient pressure to the fragments to reunite them to the column, then severing the column into the desired sizes, and finally rolling said face to smooth down the edges formed during the severing of the column.
3. The method herein described of making ornamental-faced brick, consisting in continuously forming a column of the plastic clay, continuously roughening one face of the column and simultaneously producing thereon a series of irregularly-shaped and irregularly-spaced bark-like shavings, then pressing the fragments against the face from which they were formed, the pressure being sufficient to reunite the shavings to the column without destroying the bark-like configuration thereof.
4. The method herein set forth of manufacturing ornamental-faced brick, consisting in continuously forming the plastic clay into a column and continuously shaving a thin slice from one face of the column; the slice being of such thickness that it breaks up into irregular fragments by the act of severing the slice, the severed fragments being distributed at irregular distances from each other along the face of the column, and then reuniting the fragments by pressure to that face of the column from which they were severed, whereby the fragments will be in relief and the surrounding surface of the face of the column will form a roughened back-ground, and severing the column into the desired sizes.
5. The method herein described of manufacturing ornamental-faced brick, consisting in continuously forming the plastic clay into a column, continuously severing or shaving a thin slice from one face of the column and simultaneously breaking up said slice into irregularly-shaped fragments and distributing them along the surface from which they were cut, and then reuniting the fragments to the column, leaving the fragments in relief on said face, and severing the column into the desired sizes.
6. The method herein described of making ornamental-faced brick, consisting in continuously forming a column of the plastic clay, then severing a thin shaving off one face of the clay to thereby roughen said face, said thin shaving by reason of the thinness of the same and the nature of the material being by the act of severing itself broken up into irregularly-shaped fragments, these fragments being distributed along the face from which they were cut at irregular intervals, and reuniting the fragments to said face by pressure, and severing the column into brick-sized blocks.

Signed by me at Davenport, Iowa, this 5th, day of November, 1915.

JOSEPH L. BUCKLEY.
